United States Patent Office

Des. 204,520
Patented Apr. 19, 1966

204,520

REFRIGERATOR OR SIMILAR ARTICLE

Eugene Buday, Cheyenne, Wyo., assignor to P.O.P.
Drawer Systems Corp., Newark, N.J., a corporation of
New Jersey

Filed Apr. 2, 1965, Ser. No. 84,571

Term of patent 14 years

(Cl. D67—3)

FIG. 1

FIG. 2

FIG. 1 is a perspective view of a refrigerator or similar article embodying my new design; and

FIG. 2 is a side elevational view as seen from the right side of FIG. 1.

I claim:

The ornamental design for a refrigerator or similar article, as shown.
